United States Patent Office

Des. 208,645
Patented Sept. 19, 1967

208,645

PLANTER BOX

Ralph D. Kiggins, 468 Moraga Way,
Orinda, Calif. 94563

Filed Feb. 15, 1967, Ser. No. 5,816

Term of patent 14 years

(Cl. D35—3)

I claim:

The ornamental design for a planter box substantially as shown.
